IGNITION SYSTEMS FOR INTERNAL
COMBUSTION ENGINES
John Mathias Pelikan, 2 Yennicock Drive,
Port Washington, N.Y.
Filed July 21, 1961, Ser. No. 125,689
5 Claims. (Cl. 123—149)

This invention relates to ignition systems for internal combustion engines and more particularly to ignition spark generators of the magneto type characterized by extreme simplicity of design.

The primary object of the invention is the provision of a spark generative system for ignition purposes in which the rate of change of the magneto-motive forces or total flux is intense enough for effecting a spark across a preset gap only during precise intervals in relation to the pattern of piston movement but in which the rate of change is sufficiently rapid during such intervals to induce a current of sufficient voltage and energy to effect a spark of adequate length and intensity for ignition purposes. This eliminates the need for any timing devices or other moving parts in the ignition system.

The above object is accomplished, in accordance with the principles of the present invention, by providing means preferably integrated with the moving piston itself to effect an extremely rapid build-up of a magnetizing force to a simply contructed yet efficient flux path from which an induction coil may derive accurately timed sharp impulses of high potential current suitable for energization of the ignition spark gap in the engine cylinder.

The accompanying drawing illustrates physical apparatus operable in the manner suggested above and for accomplishing the objects of the invention, and in such drawing—

FIGURE 1 is a sectional view of an ignition system constructed according to the principles of my invention; and

FIGURE 2 is a modification of the system of FIGURE 1.

Referring first to FIGURE 1, reference numeral 10 designates the wall structure of a cylinder of an internal combustion engine in which is slideably received a piston 11. The wall 10 is made of cast iron or other magnetic material, and the piston 11 may be of aluminum in accordance with usual practice. Suitably secured to the upper end of cylinder 10 is a head structure 12 which may also be of aluminum.

Screw-threadably received in a tapped bore formed in the wall structure is a soft iron stud 13 to the top of which is connected a horizontally disposed bar 14 which is also made of soft iron to provide a low-reluctance flux path for the magnetic circuit of the apparatus. Rigidly secured to and depending from the bar 14 is a stud-like body member 15 also formed of low-reluctance material and which is screw-threadably received at its lower end in an aperture formed in the head structure 12. Body member 15 has a flat lower end 16 and a passageway or bore 17 therethrough through which extends a ceramically insulated conductor 18. The bottom end of the conductor 18 cooperates with radially inward extending points 19 attached to the inner wall of the bore 17 to provide a spark gap. This gap is spaced upwardly a slight distance from the bottom 16 of the body member 15.

Encircling the body member 15 is an induction coil 20 made up of the large number of turns and having one end terminal of its wire connected to the body member 15 as shown at 21 while the other terminal is connected to the conductor 18 as shown at 22. To provide a magnetomotive force or source of flux a coil 23 is wound around the stud 13, and during operation of the apparatus this coil is connected to a suitable source of direct current.

2

Normally, the magnetic circuit comprised of the stud 13, bar 14 and body member 15 is open so that little or no flux flows longitudinally through the body member 15 and through the center of the coil 20. To effect an extremely rapid build-up in this flux path to induce a high potential across the terminals of the coil 20, a flat bar or disc 23 of magnetic material is secured on the top of the piston 11, and as shown in the drawing, this part 23' has sliding contact with the cylinder side wall material 10. When the piston 11 is moved to its topmost position, the block moves into very close proximity with the flat bottom surface 16 of the body member 15. This action substantially closes the air gap at the bottom surface 16 and thus substantially closes the magnetic circuit through stud 13, bar 14 and body member 15. As this takes place, there is a very rapid build-up of total flux in the body member 15 to induce a high potential in the coil 20 which is applied to the spark gap through conductor 18 and the point or points 19. As soon as the generated potential equals or exceeds the break-down voltage of the spark gap, an ignition spark will appear across this gap. At low piston speeds, the rate of change of the total flux flowing in the magnetic circuit will not reach the value required to generate the arcing potential until the piston is substantially in its uppermost position and the air gap almost completely eliminated. At higher piston speeds, the required rate of change and total flux will be achieved earlier in the engine cycle whereby a degree of automatic spark advance will be achieved. The timing may also be controlled by adjusting the body member 15 upwardly and outwardly, although it should be understood that if the air gap at the face 16 is appreciably lengthened a higher piston speed will be required when starting the engine.

It should be particularly noted that since the flat bottom surface 16 of the member 15 is of appreciable area and is parallel to the top surface of the magnetic bridging member 23' the reluctance of the magnetic circuit will decrease very rapidly as the piston approaches the top of its stroke thereby enabling the required rapid build-up of flux to be achieved. When the engine is on dead center the time dwell of the piston in its upper position will, of course, stabilize the flux flow at its maximum intensity whereby no potential will be generated in the coil 20. However, as the piston begins to move downward the lengthening air gap in the magnetic circuit will rapidly decrease the flow of flux and another or second spark will appear at the gap. Normally this secondary spark is not objectionable and may even be advantageous but, if desired, it can readily be eliminated by connecting a diode in the output circuit of the coil 20. Also, while an electromagnet (13, 23) is shown in FIGURE 1 to provide the magnetomotive force, it should readily be apparent that a permanent magnet may be substituted therefor to provide the source of magnetic flux for the magnetic circuit. In this modification, anyone of the parts 13, 14 and 15 may in itself be constructed as a permanent magnet.

In the embodiment of the invention shown in FIGURE 2, the arrangement and parts are generally similar to the system of FIGURE 1, the principal difference being that the source of magnetomotive force is in the form of a permanent magnet carried on top of the piston 11. This magnet, designated by reference numeral 33, is preferably of the ceramic type to withstand the heat of combustion in the engine and is in the form of a bar, as shown. Again, the cylinder wall structure 10 is of magnet material and the cylinder head, designated in FIGURE 2 by reference numeral 12', is again preferably of some non-magnetic material such as aluminum. Magnet 33 is centrally disposed on piston 11 and has a flat upper surface which is parallel with the flat bottom surface 16' of the body member 15' of the spark plug structure. Again, encircling this

body member is an induction coil 20 one terminal of which is electrically connected to the body member 15 as at 21' while the other output terminal is connected to the conductor 18' which extends through an opening in the body member 15' and is insulated from this body member by porcelain insulation 34. Since the bar magnet 33 does not extend to the side wall of the cylinder, I provide in the upper portion of the combustion chamber a bridging block 35 of a suitable nonretentive magnetic material which is in contact with the magnetic material of the side wall structure 10 of the cylinder and which has an end face across which one end face of the magnet 33 is adapted to pass closely as the piston approaches the top of a stroke. Again, the air gap in the magnetic circuit is rapidly and efficiently closed by the relative closing movement of the large flat surfaces 16' and the top of bar 33.

The principle of operation of the assembly of FIGURE 2 is substantially the same as in the embodiment of FIGURE 1, it being apparent that as the piston 11 and magnet 33 approach the upper end of their stroke the magnetic circuit comprised of the stud 13, bar 14, body member 15', magnet 33, block 35, and a portion of the cylinder wall, will be substantially closed. Simultaneously the magnetomotive force supplied by the magnet 33 will be coupled into this circuit so that a rapid build-up of flux in the same will be effected as the piston approaches the upper end of its stroke. This change of flux density in the coil 20 induces a high voltage therein to energize the spark gap shown as comprised of the lower end of conductor 18 and the point or points which extend inwardly from the annular lower portion of the body member 15'.

In either of the disclosed embodiments of the invention the coils and conductors which may be otherwise subject to water and moisture damage may be completely encapsulated in a suitable water and moisture-proof material so that theoretically the engine can operate under water if a suitable air intake and exhaust is provided.

It should now be apparent that I have provided an improved ignition system for internal combustion engines of the magneto type which does not require any moving parts in addition to the conventional piston of the engine, which is very simple in design and thus inexpensive to construct, and which inherently controls the timing of the spark in relation to the cycle of movement of the piston. Further, the system provides for an automatic spark advance in relation to the speed of piston travel and therefore in relation to the r.p.m. output of the crankshaft of the engine. Also, since the ignition system of the invention does not require any moving parts on the outside of the combustion chamber, the system may be completely encapsulated and thus remain operative under severe water and moisture conditions. In both embodiments of the invention illustrated, the spark plug assembly may be readily adjusted inwardly and outwardly of the cylinder to vary the dimension of the final air gap or to regulate the timing as described above. The threaded shanks of the body members 15 and 15' of the spark plug structures are sufficiently long to accommodate the lock nuts shown, and it should be apparent that upon loosing these devices the body members 15 and 15' may be finely adjusted inwardly or outwardly, as desired.

Having thus described my invention what I claim is new and desire to secure by Letters Patent is:

1. An ignition system; for an internal combustion engine of the kind having a piston and a cylinder whose side wall structure is of magnetic material while its head is of non-magnetic material; means extending through said head to a position closely adjacent the top portion of said piston in said cylinder and connected to said structure to establish a low reluctance flux path, an induction coil encircling said path, means including the first mentioned means and an insulated conductor leading into the combustion space of said cylinder for establishing a high tension circuit terminating at a spark gap within said space, said circuit being connected to the output of said coil,

means establishing a magnetomotive force, and means operative upon said piston reaching its top position to substantially close said path and to apply said force to said path whereby the rapid build-up of flux in the path within said coil will generate a high-voltage surge in said circuit to energize the spark gap as the piston approaches the top of its stroke.

2. An ignition system; for an internal combustion engine of the kind having a piston and a cylinder whose side wall structure is of magnetic material while its head is of non-magnetic material; a plug having a body member of magnetic current-conductive material extending through said head to an adjusted position wherein its inner end is closely spaced from the top position of said piston, means interconnecting said structure and member to establish a low-reluctance flux path, an induction coil about said path, an insulated conductor extending through said member and forming at its inner end a spark gap with said member, said coil having its output connected to said member and conductor, means establishing a magnetomotive force, and means carried by the upper end of said piston to substantially close said path and to apply said force to said path whereby the rapid build-up of flux in the path within said coil will generate a high-voltage surge to energize the spark gap as the piston approaches the top of its stroke.

3. An ignition system for an engine having a combustion chamber and a piston slideable therein comprising a normally open low-reluctance magnetic circuit, an induction coil encircling said circuit and connected to a spark gap within said chamber, means to provide a magnetomotive force, and means operative upon said piston reaching its top position to rapidly and substantially close said magnetic circuit while effectively applying said force to said circuit whereby the rapid build-up of flux in said circuit will induce a high voltage surge in said coil to energize the spark gap as the piston approaches the top of its stroke, said magnetic circuit including a flat fixed pole face and said operative means comprising a bridging piece of magnetic material carried by the upper end of the piston and having a flat pole face parallel with said fixed pole face, said faces being so oriented as to have relative movement normal to their planes.

4. An ignition system for an engine having a combustion chamber and a piston slideable therein comprising a normally open low-reluctance magnetic circuit, an induction coil encircling said circuit and connected to a spark gap within said chamber, means to provide a magnetomotive force, and means operative upon said piston reaching its top position to rapidly and substantially close said magnetic circuit while effectively applying said force to said circuit whereby the rapid build-up of flux in said circuit will induce a high voltage surge in said coil to energize the spark gap as the piston approaches the top of its stroke, said chamber being formed of magnetic material at least in its side wall and said magnetic circuit being connected to said material and including a magnetic current-conductive plug extending through the head wall of said chamber, said plug having a longitudinal bore therein for the passage of a ceramically insulated conductor forming at its lower end one terminal of said gap, said plug having a flat bottom surface, and at least an appreciable thickness of the top extremity of said piston being formed of magnetic material having a flat top surface adapted to move into close proximity with the bottom surface of said plug to thereby substantially close said magnetic circuit.

5. A system according to claim 4 in which said plug is adjustable as to vertical position with respect to the cylinder to vary the thickness of the air gap between said flat surfaces.
